BUCKLE FOR A SANITARY BELT

Estella E. Statter, Hutchinson County, S. Dak.

Application January 31, 1951, Serial No. 14,056

Term of patent 14 years

(Cl. D17—9)

To all whom it may concern:

Be it known that I, Estella E. Statter, a citizen of the United States and a resident of the county of Hutchinson, and the State of South Dakota, have invented a new, original, and ornamental Design for a Buckle for a Sanitary Belt, of which the following is the specification, reference being had to the accompanying drawing forming part thereof.

I claim:

The ornamental design for a buckle for a sanitary belt, substantially as shown.

ESTELLA E. STATTER.
